[57] CLAIM

The ornamental design for a kitchen brush handle, as shown and described.

DESCRIPTION

FIG. 1 is a top plan view of a kitchen brush handle showing my new design;

FIG. 2 is a bottom plan view thereof;

FIG. 3 is a right-side elevational view thereof;

FIG. 4 is a left-side elevational view thereof;

FIG. 5 is a front elevational view thereof; and

FIG. 6 is a rear elevational view thereof.

The bristles shown in dotted outline in the drawings are for illustrative purposes only and form no part of the claimed design.
